(57) **CLAIM**

The ornamental design for a slipper as shown and described.

DESCRIPTION

FIG. 1 is a front, left and top perspective view of a slipper, showing my design.

FIG. 2 is a rear, right and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

A slipper for the right foot is a mirror image of the slipper for the left foot as shown in FIGS. 1 to 8 and is also claimed. The broken lines shown in the drawings are included for the purpose of illustrating portions of the slipper that form no part of the claimed design.
